US00D706259S

(12) **United States Design Patent**
Myung et al.

(10) **Patent No.:** US D706,259 S
(45) **Date of Patent:** ** Jun. 3, 2014

(54) **NOTEBOOK COMPUTER**

(71) Applicant: **Samsung Electronics Co., Ltd.**, Suwon-si (KR)

(72) Inventors: **Ji-Eun Myung**, Seoul (KR); **Son-Young Lee**, Seoul (KR); **Won-Suk Chung**, Seoul (KR); **Sang-Won Yoon**, Seoul (KR)

(73) Assignee: **Samsung Electronics Co., Ltd.**, Suwon-si (KR)

(**) Term: **14 Years**

(21) Appl. No.: **29/446,941**

(22) Filed: **Feb. 28, 2013**

(30) **Foreign Application Priority Data**

Aug. 29, 2012 (KR) 30-2012-0041435
